IRVIN E. BARRICKLOW, OF SAN FRANCISCO, CALIFORNIA.

CARBURETER.

1,312,469.

Specification of Letters Patent. Patented Aug. 5, 1919.

Application filed December 4, 1917. Serial No. 205,293.

To all whom it may concern:

Be it known that I, IRVIN E. BARRICKLOW, a citizen of the United States, residing at the city and county of San Francisco and 5 State of California, have invented new and useful Improvements in Carbureters, of which the following is a specification.

This invention relates to a carbureter, and particularly to improvements on the structure shown in my co-pending application 10 entitled "carbureter," filed October 18th, 1917, Serial Number 197,233.

One of the objects of the present invention is to provide a simple, compact carbureter which is particularly designed for handling low grade fuels, such as distillate, kerosene, and the like, and in which gasoline may be employed for starting the engine and the lower grade fuel for running 20 the engine under load when the engine and carbureter have been sufficiently heated by the gasoline. Another object of the invention is to provide a novel form of throttle valve which is so positioned that it regulates 25 the volume of air admitted through the primary air inlet of the carbureter, thereby permitting the formation of a partial vacuum within the carbureter and around the spray nozzle. This is of great importance 30 as low grade fuels atomize more readily and form a more homogeneous mixture with air under a partial vacuum. Another object of the invention is to heat the atomized fuel and air during its passage through 35 the mixing chamber of the carbureter. Another object is to provide a novel mechanism for operating the throttle valve and in conjunction therewith means for regulating the lift of the needle valve in the spray nozzle. Further objects will hereinafter 40 appear.

The invention consists of the parts and the construction and combination of parts as hereinafter more fully described and 45 claimed, having reference to the accompanying drawings, in which—

Figure 1 is a central, vertical, longitudinal section through the carbureter.

Fig. 2 is a similar section, taken at right 50 angles to Fig. 1.

Fig. 3 is a side elevation of the carbureter.

Fig. 4 is a section taken on line 4—4 of 55 Fig. 1.

Referring to the drawings in detail, A indicates the casing of the carbureter, which in this instance is cylindrical in shape and

elongated, as shown. The upper end of the casing is flanged, as at 2, to permit it to be attached in the usual manner to the inlet manifold of an engine, while the lower end 60 is entirely closed by a bottom member 3 which is screwed into an annular flange 4 formed on the casing. Formed above the flange 4 is an annular opening 5, and supporting the flange with relation to the main 65 casing of the carbureter is a plurality of lugs 6. These lugs are four in number and are merely provided for the purpose of supporting the flange 4 and therefore to a certain extent divide the annular opening into 70 four separate openings, as shown in Fig. 3.

Slidably mounted interiorly of the casing is a piston valve 7 which will hereinafter be known as the throttle valve. This valve is attached to a sliding frame generally indicated at 8, and as this frame is provided with means for raising and lowering the same within the casing, it can readily be seen that the throttle valve 7 may be raised to cover or uncover the opening 5 which 80 forms the primary or main air intake of the carbureter. The bottom section 3 is provided with a three-way valve 9 and a lever 10 which may be connected, through a rod 75 or any other suitable means, by which the valve may be turned to register with one fuel passage or the other, such as shown at 11 and 12; the fuel passage 11 being for instance connected with a source of gasoline supply while the fuel passage 12 may be 90 connected with a source of low gravity fuel supply, such as distillate, kerosene, or the like. The turning of the valve 3 permits one fuel or the other to be delivered to the spray nozzle generally indicated at 13. 95

This nozzle 13 is formed as a part of the bottom section and the discharge of fuel through the spray nozzle is in this instance regulated by a weighted needle valve, generally indicated at 14. This needle valve is 100 secured upon a stem 15, which is slidably mounted in the sliding frame 8 (see Figs. 1 and 2) and the lift of the valve is under all conditions controlled by a cam 16, as will hereinafter be described. Surrounding the 105 spray nozzle and spaced therefrom is a cone-shaped cap 17. This cap is provided with an annular shoulder 18 which forms a seat for a valve 19. This valve will hereinafter be termed the secondary valve, and it is normally held on the seat 18 by means of downwardly projecting guide pins 20 which are 110

surrounded by springs 21 and guided by extensions 22 formed in the bottom section of the carbureter.

- The cone-shaped cap 17 is, as previously described, spaced from the spray nozzle and is held in this position by co-relative arms 23, secured on the spray nozzle or formed integrally therewith. The openings formed between said arms permit air, when the 5 throttle valve 7 is opened, to pass through the openings 5 and the openings formed between the arms 23, and then up through the annular space formed between the cap 17 and the tip of the spray nozzle. The air 10 thus entering in an annular stream strikes the head 14^a formed on the needle valve and is thus deflected outwardly, as indicated by the arrows (see Fig. 1).

- The valve 19 normally retains its seat 20 when the engine is idling or operating under comparatively slow speeds, but an increase of engine speed above a certain number of revolutions produces a vacuum sufficiently high within the carbureter to lift the valve 25 19 from its seat, thus permitting a portion of the air admitted through the openings 5 to pass between the seat 18 and the valve 19 directly into the mixing chamber, it being understood, of course, that a considerable 30 volume of air is simultaneously passing through the annular passage formed between the nozzle and the cap 17. The two streams of air will thus meet or cross each other, as shown by the arrows, thereby producing an ideal atomizing or mixing action 35 which thoroughly breaks up the fuel discharging from the spray nozzle.

- This atomizing action is further facilitated when the spray discharging from the 40 nozzle strikes the lower surface of the head 14^a, formed on the needle. This head being round and tapered as shown forms an ideal deflecting surface for evenly spreading the fuel particles discharging from the spray 45 nozzle and also forms a deflector for the air passing through the annular passage formed between the cap and the spray nozzle.

- The structure just described relates entirely to mechanical means for atomizing 50 or breaking up the fuel and for forming a homogeneous mixture between the fuel and the incoming air. Other means have been provided for further assisting the atomizing action and for producing a homogeneous mixture before the air and fuel can leave 55 the carbureter. The additional means just referred to is produced by two entirely different and separate actions, one being produced by heat and the other by a vacuum. 60 The heating of the mixture is produced by placing a plurality of superposed tubes 25 above the spray nozzle. These tubes are connected at one end with an intake chamber 26, which in turn is connected through a 65 flexible tube, or other suitable means, with

the exhaust manifold and at the opposite end with a discharging chamber 27, which in turn may be provided with a pipe which returns the exhaust gases to the exhaust manifold or to any other convenient point. 70 The exhaust gases admitted to chamber 26 pass through the tubes 25 and then discharge through the chamber 27 and the pipe connected therewith from where they may be returned to the main exhaust pipe or any 75 other suitable point. The exhaust gases in their passage through the tube 25 cause said tubes to become extremely hot and they, therefore, serve as a means for heating the air and atomizing fuel during their passage 80 through the mixing chamber of the carbureter. The tubes 25 also serve as deflectors between which the air and atomized fuel must necessarily pass, thereby further increasing the atomizing and mixing action of 85 fuel and air.

The second feature, *i. e.* the vacuum spoken of, is produced by placing the throttle valve at the lower end of the casing at a point where it regulates the volume of air admitted through the main or primary air inlet of the carbureter. This naturally creates a vacuum within the carbureter and around the spray nozzle and, therefore, permits the fuel particles to become more readily 95 atomized, due to the fact that any liquid material will atomize or evaporate more readily in a vacuum than under atmospheric pressure. The several features here provided permit the formation of a practically 100 homogeneous mixture of fuel and air as it can readily be seen that not only mechanical means have been provided for producing an ideal atomizing action but vacuum and heat are also utilized in conjunction therewith 105 for the purpose of furthering the atomizing action and the mixing of fuel and air.

The lifting frame 8, to which the throttle valve 7 is secured, is raised and lowered within the casing in the following manner: 110 Journaled in the upper end of the casing is a sleeve shaft 30 and secured on said shaft is a lever 31. This lever is provided with a pin 32 which enters the slotted extension 33 formed upon the sliding frame. The sleeve 115 shaft is also provided with a lever 34 which is operated in the usual manner both by the throttle lever on the steering wheel and by the accelerator. Movement of the lever 34 will, therefore, turn the sleeve shaft 30 and 120 the lever 31 and movement is thereby transmitted to raise or lower the frame 8 and the throttle valve connected therewith.

The cam 16 regulating the lift of the needle valve 14 is secured upon a shaft 35 125 which passes through the sleeve shaft 30. This shaft is also provided with a lever 36 which is adapted to move in unison with the lever 34, the lever 36 being connected with the lever 34 by means of an adjusting screw 130

37 and a spring 38. The screw 37 and spring 38 serve the purpose of changing the position of the cam 16 with relation to the sliding frame and therefore permit the lift of the needle valve to be adjusted with relation to the opening of the throttle valve. The cam 16 serves as a positive means for regulating the lift of the needle valve and while the lever 31 serves as a means for positively 10 lifting the throttle valve and as one is adjustable with relation to the other it is possible to maintain a constant proportion of fuel and air regardless of the position of either the throttle valve or the needle valve. 15 This is also of considerable importance as a uniform mixture may be maintained practically under all conditions. This feature is, however, covered in my copending application previously referred to and need not be 20 further described.

Secured on the upper end of the lifting frame is a sleeve valve 40. This valve is adapted to cover or uncover a series of perforations 41 formed near the upper end of 25 the casing and it is merely provided for the purpose of serving as an auxiliary air valve, that is, it may or it may not be used, as it is adjustably secured on a threaded extension 42 formed on the upper end of the frame. 30 Formed exteriorly of the casing is an annular shoulder 43 and resting upon said shoulder and turnably mounted on the casing is a ring valve 44 which is also perforated, as shown at 45. This ring valve may 35 be turned to bring its openings into or out of register with the openings 41, thereby serving as a means for regulating the amount of auxiliary air admitted at this point. Adjusting of the sleeve valve 40 by 40 turning thereof permits it to be set so that it will never uncover the openings 41 even though the throttle valve is lifted to its extreme position, and it can, therefore, be seen that it may be used, if desired, or set in a 45 position where it will not operate. However, it may serve the function of an auxiliary air valve whenever desired by merely raising it vertically on the threaded extension 42 and securing it when so adjusted by a lock nut 50 42^a. The carbureter may otherwise be provided with a valve, such as shown at 50. This valve may be connected with a source of water supply or with the radiator to permit any steam generated to enter the carbureter 55 when the valve is in the position of Fig. 4, this valve being opened or closed at the will of the operator by a lever extension 51, such as shown. While it is particularly adapted for admitting steam or water, 60 it may also serve as an auxiliary air valve as the type of valve employed is a three-way valve and air may, therefore, enter at the point 52.

Secured to the stem 15 supporting the 65 needle valve is a collar 15^a, and secured to

the sliding frame 8 is a spring arm 60. This spring arm straddles the stem 15 and is adapted to engage the collar and lift the valve from its seat when the sliding frame is lifted to its extreme uppermost position. 70 The spring and collar shown are merely provided for the purpose of priming the carbureter when starting. That is, when the engine is standing still before starting it has been found advantageous to lift the 75 needle valve and permit a certain quantity of fuel, for instance gasoline, to collect in the pocket 61 formed below the primary air inlet 5. The sliding frame is then moved down to close the throttle valve and the engine may then be started, thus permitting a very rich mixture to enter the cylinders during the first few revolutions of the engine when starting. Gasoline is, of course, preferably employed when starting until the engine and the tubes 25 passing through the carbureter have been sufficiently heated. The 80 low grade fuel may then be turned on by merely changing the position of the valve 9.

While two auxiliary air valves are here 90 shown, one being operated in conjunction with the throttle and the other, such as shown at 50, being operated independently thereof, it is obvious that both or either may be eliminated, if desired. Also I wish it 95 understood that the materials and finish of the several parts of the carbureter may be such as the experience and judgment of the manufacturer may dictate and that various changes in form, proportions and minor 100 details of construction may be resorted to within the scope of the appended claims and that I do not wish to limit myself to the specific design and construction here shown.

Having thus described my invention, what 105 I claim and desire to secure by Letters Patent is—

1. In a carbureter, a casing having an air inlet, a slidable valve controlling said inlet, a fuel nozzle in the casing, a slidable valve 110 controlling the fuel nozzle, operating means in the casing rigidly connected to the first valve and slidably connected to the second valve to allow the latter to slide independent of the operating means, means for raising and lowering said operating means and means controlled by the raising and lowering means for controlling the extent of upward movement of the slidable valve by engagement with the latter. 115

2. In a carbureter, a casing having an air inlet, a slidable valve controlling said inlet, a fuel nozzle in the casing, a slidable valve controlling the fuel nozzle, operating means in the casing rigidly connected to the first 125 valve and slidably connected to the second valve to allow the latter to slide independent of the operating means, means for raising and lowering said operating means, and means borne by the operating means to posi- 130

tively raise the second valve upon predetermined movement of said operating means and means controlled by the raising and lowering means for controlling the extent of upward movement of the slideable valve by engagement with the latter.

3. A carbureter comprising a casing open at its upper end and closed at the lower end, a primary, annular air inlet opening formed near the lower end of the casing, a piston throttle valve slidably mounted in the casing adapted to open or close said annular opening, a spray nozzle within the casing, means for delivering liquid fuel to said nozzle, a sliding frame within the casing to which the throttle valve is secured, means for raising and lowering said frame, a weighted needle valve supported in alignment with the spray nozzle and adapted to regulate the amount of fuel discharged thereby, and means on the sliding frame for raising the needle valve with relation to the spray nozzle.

4. A carbureter comprising a casing open at its upper end and closed at the lower end, a primary, annular air inlet opening formed near the lower end of the casing, a piston throttle valve slidably mounted in the casing adapted to open or close said annular opening, a spray nozzle within the casing, means for delivering liquid fuel to said nozzle, a sliding frame within the casing to which the throttle valve is secured, means for raising and lowering said frame, a stem slidably mounted in the sliding frame, a weighted needle valve secured on the stem adapted to enter the mouth of the spray nozzle, and means on the sliding frame for raising the needle valve away from the spray nozzle.

- 40 5. A carbureter comprising a casing open at its upper end and closed at the lower end, a primary, annular air inlet opening formed near the lower end of the casing, a piston throttle valve slidably mounted in the casing adapted to open or close said annular opening, a spray nozzle within the casing, means for delivering liquid fuel to said nozzle, a sliding frame within the casing to which the throttle valve is secured, means for raising and lowering said frame, a stem slidably mounted in the sliding frame, a weighted needle valve secured on the stem adapted to enter the mouth of the spray nozzle, and means on the sliding frame for raising the needle valve away from the spray nozzle, said means comprising a collar secured on the needle valve stem, and a finger on the frame adapted to engage said collar when the frame is raised to its extreme uppermost position.

6. A carbureter comprising a cylindrical-shaped casing open at its upper end, a bottom member forming a closure for the lower

end of the casing, an annular inlet opening formed in the casing above the bottom section, a piston throttle valve slidably mounted within the casing adapted to open or close the annular air inlet opening, a spray nozzle carried by the bottom section, means for delivering fuel thereto, a needle valve adapted to regulate the discharge of fuel from the nozzle, a cone-shaped cap surrounding the nozzle and spaced therefrom, an annular seat on the lower end of said cap, a valve slidably mounted within the throttle valve engaging said seat, means for retaining said valve in normal engagement with said seat, and means for raising and lowering the throttle valve independently of said last named valve.

7. A carbureter comprising a cylindrical-shaped casing open at its upper end, a bottom member forming a closure for the lower end of the casing, an annular inlet opening formed in the casing above the bottom section, a piston throttle valve slidably mounted within the casing adapted to open or close the annular air inlet opening, a spray nozzle carried by the bottom section, means for delivering fuel thereto, a needle valve adapted to regulate the discharge of fuel from the nozzle, a cone-shaped cap surrounding the nozzle and spaced therefrom, an annular seat on the lower end of said cap, a valve slidably mounted within the throttle valve engaging said seat, means for retaining said valve in normal engagement with said seat, a sliding frame mounted within the casing to which the throttle valve is secured, a stem slidably mounted in said sliding frame supporting the needle valve, means for raising and lowering the sliding frame together with the throttle valve, and means coöperating with said means for positively regulating the position of the needle valve with relation to the spray nozzle.

8. A carbureter comprising a cylindrical-shaped casing open at its upper end, a bottom member forming a closure for the lower end of the casing, an annular inlet opening formed in the casing above the bottom section, a piston throttle valve slidably mounted within the casing adapted to open or close the annular air inlet opening, a spray nozzle carried by the bottom section, means for delivering fuel thereto, a sliding frame within the casing to which the throttle valve is secured, a stem slidably mounted in said sliding frame, a weighted needle valve secured on said stem adapted to enter the mouth of the spray nozzle, means on the sliding frame for lifting the needle valve away from the spray nozzle, means for lifting the sliding frame, together with the throttle valve secured thereto, and means

operable in conjunction with said means for positively regulating the lift of the weighted needle valve.

9. A carbureter comprising a cylindrical-shaped casing open at its upper end, a bottom member forming a closure for the lower end of the casing, an annular inlet opening formed in the casing above the bottom section, a piston throttle valve slidably mounted within the casing adapted to open or close the annular air inlet opening, a spray nozzle carried by the bottom section, means for delivering fuel thereto, a sliding frame within the casing to which the throttle valve is secured, a stem slidably mounted in said sliding frame, a weighted needle valve secured on said stem adapted to enter the mouth of the spray nozzle, a plurality of auxiliary air inlet openings formed in the casing near its upper end, an auxiliary air valve adjustably secured to the sliding frame adapted to cover or uncover said auxiliary air inlet openings, and means for raising and lowering the sliding frame, together with the throttle valve and the auxiliary air inlet valve carried thereby.

10. A carbureter comprising a cylindrical-shaped casing open at its upper end, a bottom member forming a closure for the lower end of the casing, an annular inlet opening formed in the casing above the bottom section, a piston throttle valve slidably mounted within the casing adapted to open or close the annular air inlet opening, a spray nozzle carried by the bottom section, means for delivering fuel thereto, a sliding frame within the casing to which the throttle valve is secured, a stem slidably mounted in said sliding frame, a weighted needle valve secured on said stem adapted to enter the mouth of the spray nozzle, a slotted extension on the sliding frame, a shaft extending through the casing and journaled therein, a crank arm on said shaft, a pin on said crank arm adapted to engage the slotted extension on the sliding frame, and means for turning the shaft and the crank arm carried thereby to raise and lower the sliding frame together with the throttle valve secured thereto.

11. A carbureter comprising a cylindrical-shaped casing open at its upper end, a bottom member forming a closure for the lower end of the casing, an annular inlet opening formed in the casing above the bottom section, a piston throttle valve slidably mounted within the casing adapted to open or close the annular air inlet opening, a spray nozzle carried by the bottom section, means for delivering fuel thereto, a sliding frame within the casing to which the throttle valve is secured, a stem slidably mounted in said sliding frame, a weighted needle valve secured on said stem adapted to enter the mouth of the spray nozzle, a slotted extension on the slid-

ing frame, a shaft extending through the casing and journaled therein, a sleeve journaled on said shaft, a cam secured on the shaft in alignment with the needle valve stem, a crank arm secured on the sleeve, a pin on said crank arm engaging the slotted extension on the sliding frame, means for turning the shaft and the sleeve in unison, and means for adjusting the sleeve with relation to the shaft circumferentially.

12. A carbureter comprising a cylindrical-shaped casing open at its upper end, a bottom member forming a closure for the lower end of the casing, an annular inlet opening formed in the casing above the bottom section, a piston throttle valve slidably mounted within the casing adapted to open or close the annular air inlet opening, a spray nozzle carried by the bottom section, means for delivering fuel thereto, a sliding frame within the casing to which the throttle valve is secured, a stem slidably mounted in said sliding frame, a weighted needle valve secured on the lower end of said stem adapted to enter the mouth of the spray nozzle, a cone-shaped cap surrounding the spray nozzle and spaced from same, an annular seat on the lower end of said cap, a valve slidably mounted within the throttle valve engaging said seat, springs connected with said valve adapted to normally retain said valve on its seat, a plurality of auxiliary air inlet openings formed in the casing near the upper end, a sleeve valve carried by the sliding frame adapted to open or close said openings, means for raising and lowering the sliding frame together with the auxiliary air valve and the throttle valve, and means operable in conjunction with said means for regulating the lift of the needle valve and its stem.

13. A carbureter comprising a cylindrical-shaped casing open at its upper end, a bottom member forming a closure for the lower end of the casing, an annular inlet opening formed in the casing above the bottom section, a piston throttle valve slidably mounted within the casing adapted to open or close the annular air inlet opening, a spray nozzle carried by the bottom section, means for delivering fuel thereto, a sliding frame within the casing to which the throttle valve is secured, a stem slidably mounted in the sliding frame, a weighted needle valve secured on the lower end of said stem adapted to enter the mouth of the spray nozzle, a cone-shaped cap surrounding the spray nozzle and spaced from same, an annular seat on the lower end of said cap, a valve slidably mounted within the throttle valve engaging said seat, springs connected with said valve adapted to normally retain said valve on its seat, a plurality of auxiliary air inlet openings formed in the cas-

- ing near the upper end, a sleeve valve carried by the sliding frame adapted to open or close said openings, means for raising and lowering the sliding frame together with the auxiliary air valve and the throttle valve, means operable in conjunction with said means for regulating the lift of the needle valve and its stem, and means on the sliding frame operable independently of said last named means for raising the needle valve away from the nozzle.
14. A carbureter comprising a cylindrical-shaped casing open at its upper end, a bottom member forming a closure for the lower end of the casing, an annular inlet opening formed in the casing above the bottom section, a piston throttle valve slidably mounted within the casing adapted to open or close the annular air inlet opening, a spray nozzle carried by the bottom section, means for delivering fuel thereto, a sliding frame within the casing to which the throttle valve is secured, a stem slidably mounted in the sliding frame, a weighted needle valve secured on the lower end of said stem adapted to enter the mouth of the spray nozzle, a cone-shaped cap surrounding the spray nozzle and spaced from same, an annular seat on the lower end of said cap, a valve slidably mounted within the throttle valve engaging said seat, springs connected with said valve adapted to normally retain said valve on its seat, a plurality of auxiliary air inlet openings formed in the casing near the upper end, a sleeve valve carried by the sliding frame adapted to open or close said openings, means for raising and lowering the sliding frame together with the auxiliary air valve and the throttle valve, means operable in conjunction with said means for regulating the lift of the needle valve and its stem, a spring finger on the sliding frame, and a collar on the needle valve stem adapted to be engaged by the spring finger to lift the needle valve away from the spray nozzle when the sliding frame is lifted to its extreme uppermost position.
15. In a carbureter, a casing having an air inlet, a fuel nozzle in the casing, a valve controlling the air inlet, a valve controlling the fuel nozzle, a member rigidly secured to the air controlling valve, means to slidably support the fuel controlling valve from said member to allow the former to move independent of the latter, and actuating means common to said member and supporting means of the fuel controlling valve for engaging and operating each.
16. A carbureter comprising a cylindrical-shaped casing open at its upper end, a bottom section forming a closure for the lower end, an annular air inlet opening formed in the casing just above the bottom section, a piston throttle valve slidably mounted within the casing adapted to open or close said annular air inlet opening, a spray nozzle within the carbureter centrally disposed with relation to the throttle valve, means for delivering fuel to said spray nozzle, a needle valve adapted to regulate the discharge of fuel from the spray nozzle, a plurality of auxiliary air inlet openings formed in the casing near the upper end, a sleeve valve within the casing adapted to open and close said openings, means for lifting the throttle valve and the auxiliary air valve in unison, and means for adjusting the position of the auxiliary air valve with relation to the throttle valve in a vertical direction.
